UNITED STATES PATENT OFFICE.

AMOS NUDD, OF EXETER, NEW HAMPSHIRE.

FIRE-ENGINE.

Specification of Letters Patent No. 12,441, dated February 27, 1855.

To all whom it may concern:

Be it known that I, AMOS NUDD, of Exeter, in the county of Rockingham and State of New Hampshire, have invented 5 certain new and useful Improvements in Fire-Engines, of which the following is a full, clear, and exact description, reference being had to the annexed drawings, making part of this specification, in which—
10 Figure 1 is a plan of an engine with my improvements attached; Fig. 2, a vertical section through the same upon the line A', A'.

In fire engines as at present constructed 15 the brake lever on arriving at the end of its stroke is brought up by striking against the tub or frame work of the engine; the jar thus produced is very fatiguing to those operating the brakes, and this inconvenience 20 is by no means obviated if the brake lever is stopped before it strikes the tub. Efforts have been made to remedy the evil by the use of springs placed beneath the brake levers, and which are intended to break the 25 force of the blow with which the latter descend, but the benefit of this appliance is only partial.

To overcome entirely the disagreeable and 30 fatiguing effect above spoken of and to produce an equable motion of the brakes, without jar to those operating them, and without injury to the engine itself is the object of my present invention, which consists in connecting the brake lever with a revolving 35 shaft by means of a connecting rod, the motion of the shaft being steadied by a fly wheel, whereby an exceedingly equable and uniform motion of the brakes is obtained without jar or shock to either engine or 40 engine men.

To enable others skilled in the art to make and use my invention I will proceed to de-

scribe the manner in which I have carried it out.

In the accompanying drawings A is the 45 box or tub of the engine; B, the cylinders; C, the brake lever pivoted at f.

D is a metallic upright or standard secured to the brake lever or making a part thereof. 50

E is a shaft running in boxes upon the top of the engine.

e is a connecting rod one end of which is pivoted to the standard D and the other to the crank g upon the shaft E. Upon this shaft is secured the cog wheel G which engages with the wheel H upon the shaft I, to which is also secured the fly wheel K. 55

It is evident from the connections above described that the motion of the shaft E 60 will be nearly uniform, and that as the brake lever approaches its lowest point its momentum will be very slowly retarded, and that the brake will pass the dead center, without jar to the operatives or injury to 65 the engine an exceedingly equable and steady motion being produced—the brakes remaining motionless or nearly so while the crank is passing center, and being aided as they first commence to start again by the 70 continued motion of the crank.

I do not claim the application of a fly wheel to a fire engine or to any other machinery, but what I do claim as my invention and desire to secure by Letters Patent 75 is—

The method herein described of easing the motion of the brake lever by the attachment of a crank in the manner set forth.

AMOS NUDD.

In presence of—

HENRY F. FRENCH,
CHAS. G. CONNER.
